UNITED STATES PATENT OFFICE.

ADELMER MARCUS BATES, OF CHICAGO, ILLINOIS, ASSIGNOR TO BATES VALVE BAG COMPANY, OF CHICAGO, ILLINOIS, A CORPORATION OF WEST VIRGINIA.

TOOL FOR TYING WIRE BAG-TIES.

1,306,163.

Specification of Letters Patent. Patented June 10, 1919.

Application filed February 9, 1918. Serial No. 216,396.

To all whom it may concern:

Be it known that I, ADELMER MARCUS BATES, a citizen of the United States, residing at Chicago, in the county of Cook and State of Illinois, have invented a certain new and useful Improvement in Tools for Tying Wire Bag-Ties, of which the following is a specification.

My invention relates to improvements in means for tying bags. It has for one object to provide a convenient and simple device whereby the operator may with a minimum of effort tie or untie bags by twisting or untwisting a wire tie about the open neck thereof. Another object is to provide a tool which may be used by the same operator to tie or untie the bag without change in adjustment. Another object of my invention is to provide a tool to twist ties in opposite directions without change in adjustment. Another object is to provide a tool which may be carried and used without difficulty, fatigue, or discomfort by the operator. Another object is to provide a tool which can be used for tying a number of bags in a group even or at a considerable distance away from the operator. Other objects of my invention will appear from time to time in the specification.

30 The invention is illustrated more or less diagrammatically in the accompanying drawings, wherein

Figure 1 shows a side elevation of an operator using my tool;

35 Fig. 2 is an enlarged view of the tool; Fig. 3 is a similar enlarged view of the tool after the twisting operation has taken place showing a plan view of the tool itself; Fig. 4 is a side elevation of a modified form;

40 Fig. 5 is a plan view of a different form; Fig. 6 is a front elevation of a different form of the tie holder or hook;

45 Figs. 7, 8 and 9 are different forms of ties which may be used.

Like parts are indicated by like characters in all the figures.

50 A is a bow-shaped twisting handle flattened at A¹ and apertured at A² to engage a holding thong or cord A³ which may be fastened to the belt A⁴ of the operator. It may be tied around his waist or it may be tied on his arm depending on his convenience and preference. The handle is flattened at the opposed end and mortised as at

A⁶. Riveted to such flattened end is a single hook A⁷ which hook is adapted to engage loops A⁸ A⁸ on the opposed ends of a tie A⁹ which tie in turn is adapted to surround the puckered end A¹⁰ of a bag A¹¹.

60 In Figs. 4, 5 and 6 I have shown a different form of tie holding means. It takes the form of a broad flat hook B having slots B¹ B² forming a kind of claw. These slots are of such depth that they engage and hold the up set ends B² B² of a tie B³ and are of such depth, if necessary, that the two ties may be superposed one upon another. This hook B, with or without the slots, may also be used to twist a ring tie C. If this were 65 bent the ring tie would be placed as shown in dotted lines in Fig. 5 and whether the ring tie or upset tie is used the twisting operation is used. The difference between the ring tie and the other two ties is that 70 when the twisting operation has taken place with the ring tie you have a closed key to untwist the tie, with the other two you have two closely related ends which can be engaged either by the hand or the tool to un- 75 twist the tie.

80 It will be evident that while I have shown in my drawings an operative device, still many changes might be made both in size, shape and arrangement of parts without departing materially from the spirit of my invention and I wish, therefore, that my drawings be regarded as in a sense diagrammatic.

85 It will be understood that when the tying tool has been removed from engagement with the tie which has just been tied, it leaves the loops, if it is the hook tool, superposed one on the other and held closely together so that in transit the chances are 90 that they will never be disarranged and it will be easy to place another hook through them to untwist but when the claw which holds and twists the up set end is used it frequently happens that the up set ends, although left in such position, so they can 95 easily be gripped by the claw, will be bent together so that this becomes difficult. It is under these circumstances that the central long finger as shown becomes valuable. This 100 finger being more or less pointed can be thrust between the two ends of the tie if there is any distance at all between them and when they are forced down by it they will be wedged apart until they find their 110

place in the two slots. Thus under all practical conditions the two up set ends may be separated for untwisting.

The use and operation of my invention 5 are as follows:—

The operator having the thong which holds his tool attached to his body or arm, and frequently the operators prefer to attach it to the upper arm above the elbow, 10 approaches the work, puckers the neck of the bag by hand by gathering it together, places a tie with one loop on the single hook or if an upset end engaging one of the slots, passes the end of the tie about the 15 puckered neck of the bag, engages the free end of the tie with the twisting hook and then holding the puckered neck of the bag, preferably above the tie, backs off a little or pulls back on his right arm so as to 20 exert a tension in the thong. The purpose of exerting this tension is to make sure that a fixed axial line is located about which the twisting can take place. That fixed axial line is one parallel with and an extension 25 of the thong passing through the two ends of the handle and through the neck of the bag and where it is engaged by the tie. He then rotates the tool with his free hand rotating it about the fixed axis formed by 30 the tension in the coöperating parts until the tie is snugly twisted about the neck of the bag. The number of turns depends on the length of the tie and size of the bag. Preferably this is ordinarily about three 35 turns. He then releases the tension, un- hooks or disengages the tie and passes on to the next job. The tool is so light that he can just let go of it and when it drops down if it should strike him it does no 40 harm. The thong twists or untwists with the movement of the tool and he needs pay no attention to it. If for any reason the thong should not untwist, he can twist in the opposite direction for the next operation 45 and return the thong to normal. Experience shows that the thong is more satisfactory than the swivel. It is made of leather and twists with less friction than would a specially provided swivel device. 50 Obviously the hooks which I have shown operate so long as they engage and hold the tie. A time may come, however, when the hook will wear out, though it is of hardened steel and of long life. If it is necessary to cut away the rivets and replace the 55 worn out hook with another, the tool will be as good as new. The thong may be easily replaced and there is substantially no wear on the bow-shaped handle itself. 60 In discussing and claiming by wire tie twisting tool, I have thought of and claimed the bow-shaped part A as being an elongated body having a twisting handle or hand engaging part. Obviously the whole thing 65 is one piece but the twisting handle is that

part of the curved or off set body which is engaged by the hand of the operator when he rotates it to twist the tie.

Obviously the sole purpose of the thong and the tension exerted thereby is to fix 70 the axis of rotation of the tie while the tie is being twisted. We care nothing about the axis of rotation at any other time and in fact it is convenient to move the tool so that as twisting is taking place the axis 75 about which the tool rotates will be fixed and this fixation of this twisting axis might obviously be obtained by means other than those illustrated, though I prefer owing to their cheapness and simplicity, the thong 80 and tension apparatus. The thong, of course, when taut is in effect a rigid bar and so a rigid bar might be substituted and this would amount to keeping the thong taut at all times. 85

I claim:

1. A wire tie twisting tool comprising a bow-shaped handle body, a tie engaging member at one end, and a flexible support 90 for the other end. 90

2. A wire tie twisting tool comprising a bow-shaped handle body, a tie engaging member at one end, and flexible means coöperating with the tie engaging member for maintaining the axis located by the 95 two ends of the tool in a fixed line while the tool is being rotated to twist the tie. 95

3. A wire tie twisting tool comprising a bow-shaped handle body, a tie engaging member at one end, means coöperating with 100 the tie engaging member for maintaining the axis located by the two ends of the tool in a fixed line while the tool is being rotated to twist the tie, said means comprising flexible means for exerting a ten- 105 sion on the tool against the pull of the tie. 105

4. A wire tie twisting tool comprising a bow-shaped handle, a tie engaging member at one end, and flexible means coöperating 110 with the tie engaging member for exerting a tension on the tool along a line in continuation of the axis of rotation of the tool. 110

5. A wire tie twisting tool comprising a bow-shaped handle body, a tie engaging member at one end, means coöperating with 115 the tie engaging member for maintaining the axis located by the two ends of the tool in a fixed line while the tool is being rotated to twist the tie, said means comprising 120 means for exerting a tension on the tool against the pull of the tie, said means comprising a flexible member attached at one end to the tool, at the other end to the body 125 of the operator. 125

6. A wire tie twisting tool comprising a bow-shaped handle body, a tie engaging member at one end, means coöperating with 130 the tie engaging member for exerting a tension on the tool along a line in continuation 130

- of the axis of rotation of the tool, said means comprising a flexible member attached at one end to the tool, at the other end to the body of the operator.
5. 7. A wire tie twisting tool comprising an elongated body, forming in part a twisting handle removed from the axis joining the ends thereof, a tie engaging means at one end and a flexible support for the other end.
10. 8. A wire tie twisting tool comprising an elongated body forming in part a twisting handle removed from the axis joining the ends thereof, a tie engaging means at one end, and flexible means coöperating with the tie engaging member for maintaining the axis located by the two ends of the tool in a fixed line while the tool is being rotated to twist the tie.
15. 9. A wire tie twisting tool comprising an elongated body; forming in part a twisting handle removed from the axis joining the ends thereof, a tie engaging means at one end, means coöperating with the tie engaging member for maintaining the axis located by the two ends of the tool in a fixed line while the tool is being rotated to twist the tie, said means comprising flexible means for exerting a tension on the tool against the pull of the tie.
20. 10. A wire tie twisting tool comprising an elongated body, forming in part a twisting handle removed from the axis joining the ends thereof, a tie engaging means at one end, means coöperating with the tie engaging member for maintaining the axis located by the two ends of the tool in a fixed line while the tool is being rotated to twist the tie, said means comprising means for exerting a tension on the tool against the pull of the tie.
25. 11. A wire tie twisting tool comprising an elongated body, forming in part a twisting handle removed from the axis joining the ends thereof, a tie engaging means at one end and a flexible support for the other end.
30. 12. In a wire twisting tool for wire ties a holding claw having a tie engaging member extending substantially normal to the axis of the tool, said member being slotted at two places to engage the up set ends of the tie, an elongated finger between the two slots extending upwardly to a point above the member whereby the two tie ends may be separated.
35. 13. A wire tie twisting tool comprising a bow-shaped handle provided at one end with means for engaging the tie and at the other with securing means which permit rotation of the handle and prevent its longitudinal movement.
40. 14. A wire tie twisting tool comprising a bow-shaped handle provided at one end with means for engaging the tie and at the other with securing means which permit rotation of the handle and prevent its longitudinal movement toward the tie.
45. 15. A wire tie twisting tool comprising a bow-shaped handle provided at one end with means for engaging the tie in combination with a strap, the other end of the tool attached to the strap so as to permit rotation of the handle.

In testimony whereof I affix my signature, in the presence of two witnesses, this 2nd day of February, 1918.
